US0D1096797S

(12) **United States Design Patent** (10) **Patent No.:** **US D1,096,797 S**
Peittersen et al. (45) **Date of Patent:** **** Oct. 7, 2025**

(54) **DISPLAY SCREEN OR PORTION THEREOF WITH A GRAPHICAL USER INTERFACE WITH A CIVILITY SCORE**

(71) Applicant: **Seekr Technologies Inc.**, Vienna, VA (US)

(72) Inventors: **Rachel Peittersen**, Vienna, VA (US); **Gregory Bauwens**, Vienna, VA (US)

(73) Assignee: **SEEKR TECHNOLOGIES INC.**, Vienna, VA (US)

(**) Term: **15 Years**

(21) Appl. No.: **29/938,747**

(22) Filed: **Apr. 23, 2024**

(51) LOC (15) Cl. **14-04**

(52) U.S. Cl.

CLAIM

The ornamental design for a display screen or portion thereof with a graphical user interface with a civility score as shown and described.

DESCRIPTION

The single FIGURE is a front view of a display screen or portion thereof with a graphical user interface with a civility score.

The outermost broken lines show the display screen or portion thereof and form no part of the claimed design. The broken lines within the FIGURE show portions of the graphical user interface that form no part of the claimed design.

The Civility Score forming part of the claimed design is a trademark of SEEKR TECHNOLOGIES, INC.

1 Claim, 1 Drawing Sheet
